UNITED STATES PATENT OFFICE.

FRED W. BARKLEY, OF WINTHROP, MASSACHUSETTS, ASSIGNOR TO ALBERTO BARKLEY, OF PAINTED POST, NEW YORK.

CALCULATING MACHINE.

Application filed November 21, 1919. Serial No. 339,678.

The invention relates to a calculating machine of the type having a suitable keyboard, a novel selecting mechanism for obtaining any certain calculation which can be registered on one or more dials, an over-rotating mechanism to insure accuracy in manipulation, and a carrying over mechanism to transfer the result from one dial to the next in order.

10 The invention consists of a rotating unit provided with bars having teeth and depressions of variable lengths formed thereon, the teeth mesh with the shifting gear for rotating the numeral dial to the desired calculation position; the depressions formed in the tooth bars permit the shifting gear to pass through the said depressions of the tooth bars not selected to operate.

The object of the invention is to provide 20 a calculating machine having a novel and effective rotating selecting unit having variable length gear teeth for allowing certain numerals to be selected with ease and accuracy which is durable, practical, noiseless and cheap to manufacture.

A complete description of a calculating machine and my improvements is as follows; reference being made to the accompanying drawing of which—

30 Figure 1 is a perspective view of the calculating machine showing the operating members.

Figure 2 is a plan view of the same partly broken away, showing the operating mechanism.

Figure 3 is a longitudinal section, showing the operation crank and connections.

Figure 4 is a longitudinal section, showing the keys and selecting mechanism.

40 Figure 5 is a transverse section, showing the key and automatic locking and releasing mechanism, also showing the operating crank and connections.

Figure 6 shows the selecting mechanism with the over-rotating check in position.

Figure 7 shows carrying-over mechanism.

Figure 7A is a side view of the same.

Figure 8 is a side view of the carrying-over mechanism.

Figure 9 is a diagrammatic view of the 50 selecting mechanism.

Figure 10 is a plan view of the over-rotating check.

Figure 11 is a plan view of the carrying-over mechanism. 55

Figure 12 is a diagrammatic view showing the selecting stops.

Figure 13 shows the selecting mechanism with the over-rotating check in the operating position. 60

Figure 14 is the same, with the over-rotating check in position, and the carrying over mechanism coming into position.

Figure 15 shows the carrying-over mechanism in the operating position. 65

Figure 16 shows the reversing mechanism.

The calculating mechanism is provided with a suitable casing 11, having a cover 12, and sliding carriage 13. Formed on the 70 sliding carriage is an operating finger 14 for lifting the carriage and moving it back and forth as the calculating operations require. Also formed on the carriage is a catch 15 which co-operates with a plurality of holes 75 16 in the cover 12 for registering the carriage with the set of figured dials required to perform the calculation. Mounted in the casing 11 and cover 12 are six sets of selecting keys 17, 18, 19, 20, 21, and 22 which will give 80 a range of calculation from 1 to 999,999 and further calculation may be obtained by manipulating the carriage 12.

When the numerals are selected to be calculated, the result is obtained by rotating 85 the crank 23. To obtain a result in addition and multiplication respectively, the crank is turned in one direction, and for subtraction and division respectively the crank is turned in the opposite direction. 90 The result of the calculation is shown through the window 24 formed in the carriage 13. To clear out the figured calculation, the dials are returned to the zero position by the handle 25. The numeral showing through the window 26 indicates the 95 number of times the main operating crank 23 has been turned in relation to a given

formula to be calculated. These numerals are cleared out by rotating the handle 27. Each of the six sets of selecting keys is marked with ten numerals ranging from 5 zero to nine. Each succeeding dial marking the next order of ten in either direction.

It is obvious that by adding another set of keys the amount can be carried to a higher order of tens, and so on, according 10 to the number of sets required. As each set of numerals is the same, and as the mechanism is identical in construction and operation, a description of one unit will be sufficient. The keys are mounted on a housing 15 secured to the cover 11 which is divided into two parts in the horizontal plane. The keys are assembled with the cover 12 and then placed in position in the casing 11. The keyboard consists of three plates indicated by 30, 31, and the cover 12. These plates are secured to the transverse frames 32, 33, 34, and 35, and are held in the integral relation with each other by screws. Integral with the frame member 32 is a 20 ledge 36 on which the locking springs are mounted, these springs forming a part of the key locking mechanism, a description which will be taken up hereafter. Machined in the plate 31, which is rigid with frame, are ten slots through which the keys are free 25 to move vertically at the will of the operator. Superimposed on the plate 31 is a sliding strip 40 which is operated by the keys. Machined in the strip 40 are ten slots 30 through which the keys extend, one slot for each key. The plate 31 extends beyond the frame members 33 and 35, as indicated at 41, and serves as a support for the bell crank lever 42 of which there are six, these 35 levers shifting the gears for selecting the number indicated by the key when it is pressed downwardly into position. The selecting gear will be taken up in detail hereinafter. The bell crank lever is pivoted at 43 and is caused to swing outwardly on its pivot by the movement of the sliding plate 40; and is also held in position by one of the keys and remains locked until the key is released, after which the bell crank 45 is returned to the zero position by a spring forming a part of another mechanism, which will be described in detail in another part of the specification.

The individual keys forming a set of numerals from zero to nine, inclusive, will be indicated by the numerals of operation, composing 0, 1, 2, 3, 4, 5, 6, 7, 8, and 9. These keys are guided in their vertical movements in the cover 12 and plate 30 and are held constantly upward by the spring 45. The spring 45 encompasses the keys and the lower end of this spring rests on the rigid plate 30, the other end resting on the movable washer 46. The washer 46 is held 50 between the spring and pin. When the

key is pressed downwardly, the washer travels with it, and compresses the spring. When the key is released, the spring is forced upwardly into its normal position. The keys from 1 to 9, inclusive, are designed 55 to give a variation in travel to the sliding plate 40 which in turn imparts a swinging movement to the bell crank 42. The movement of the sliding plate 40 is determined by the angular cam surface 50 60 formed on the keys 1 to 9, inclusive. On the zero key there is no cam surface, this key being used mostly for releasing the other keys in the set from 1 to 9 inclusive. The cam surfaces 50 are of such progressive 65 dimensions that a short cam surface on key 1 in its downward movement will cause the bell crank lever 42 to move a correspondingly short distance, which through instrumentalities to be described will select the 70 numeral 1. Formed on key 9 is a cam surface having the longest dimension which will move the bell crank lever 42 sufficiently 75 to select the numeral 9. The intervening 80 gears have a range of movement equal to the distance from one to eight, which will bring the numeral to view corresponding to the key operated. The keys when operated are locked and released automatically. Formed on the keys is a lug 52 which extends outwardly from one side of the keys. The lug 52 cooperates with the longitudinal bar 53 for locking the setting up keys from 85 1 to 9 inclusive. The locking bar 53 is constantly pressed inwardly by the spring 54 which is held in position on the ledge 36 by a screw. When a key is pressed downwardly, the movement is sufficient to allow the locking bar 53 to snap over on the lug 52 thereby holding the key in its downward 90 position. When a second key in the same set is pressed downwardly, or set, it releases the first key; that is, when the second key by its downward movement swings out the locking bar it allows the said bar to lock the key in position and it also throws the said bar sufficiently to release the first key, which permits the said bar to be returned to its normal position by the 95 spring 45.

Mounted in the casing 12 is a shaft 55 which supports the six gears, indicated by 56, which are free to rotate and to move axially. Also mounted on the shaft 55 is a spring yoke 57 which grips the gear and is free to move with the gear along the shaft 55. Integral with the yoke 57 is a U shaped balancing arm 58, both legs 59 and 60 being mounted on the shaft 61. This construction 100 serves as a steady means to prevent the gears 56 from skewing in their axial travel. The bell crank 42 causes the gear 56 and depending members to travel in one direction 105 against the compression of spring 62. The spring 62 encompasses the shaft 61 and lies 110

between the leg 60 and the pin 63. When the bell crank 42 moves in the opposite direction, the spring 62 causes the gear 56 to move axially back to the starting position, or the one shown in Figure 9.

When the numerals to be calculated are selected, the device is operated to obtain a certain result. This is accomplished by the operation crank 23, which is turned one or 10 more revolutions as desired. This movement of the operation crank 23 imparts a revolving movement to the shaft 66, through the bevel gears 67 and 68, shaft 69 and bevel gears 70 and 71. The crank shaft 23 is provided with bearings 72 and 73, and the shaft 69 is mounted in the bearings 74 and 75. The shaft 66 is mounted in one side of the casing 11 and the opposite end is mounted in the partition 76. The end thrust of 15 the shaft 66 is taken up by the bevel gear 71 and collar 77. Rigidly secured to the shaft 66 are seven disks indicated at 78. The disks being identical in construction and operation, a description of one will 20 suffice. Mounted in the disks are nine bars indicated by 1, 2, 3, 4, 5, 6, 7, 8, 9, respectively which is one embodiment of my invention. These bars indicate selective gear teeth corresponding to the nine keys comprising one set. For example, when a key 25 is set, the key 5 being used for illustrative purposes such key is pushed downwardly, and this movement of the key 5 will cause the selecting gear 56 to be moved to engage the gear bar 5, of the selecting mechanism 30 thereby advancing the dial five places. The bars are rigidly secured in slots cut in the discs 78 and extend across the whole seven discs. Between each of the discs are gear 35 teeth of different lengths ranging from 1 to 9, that is, if the key 1 is pressed down, the selecting or sliding gear 56 will engage the tooth 1, Figure 12, and so on, the sliding gear 56 also engaging the teeth 1 to 9, inclusive, in accordance with the axial travel 40 of the gear 56. The distance of travel of the sliding gear 56 is limited to the axial dimension of the cage gear 80, Figure 9. In the gear bars 1 to 9 inclusive, are recesses 45 56 81 which permit the sliding gear 56 to pass through without engaging the teeth when the selecting bars are rotated.

Referring to Figure 13, this view shows one of the bars from 9 to 1 inclusive about 55 to engage the sliding gear 56. Simultaneously with this engagement the check lever 82 has dropped downwardly on the lower cam surface 83, thereby allowing the gear 84 to rotate upon the further movement of the 60 gear bars mounted in the disk 78. As we have selected nine as the numeral to be designated, we will now rotate the disc 78 the distance of nine gear bars, each gear bar having a corresponding tooth on the sliding 65 gear 56. The rotating movement of the

sliding gear 56 imparts a corresponding movement to the cage gear 80, gear 84, and dial gear 85. The dial gear has rotated sufficiently to show the numeral 9 through the window 24, thereby indicating the numeral required. If the key 1 had been selected the gear bar 1 would have engaged one tooth of the selecting gear 56 and with further rotation of the disc 78, the gear 56 would have passed through the recesses 81 missing eight teeth, thereby registering the numeral one on the dial. After the gear strips 1 to 9 inclusive, pass by the selecting gear 56, the over-rotating check 82 is raised to the upper cam surface 86, thereby holding the gear train in the position designated by the selecting key as shown in Figure 14.

The over-rotating check 82 having a wiping foot which follows the cam contour of the disc 78 and raises and lowers the check lever as conditions require. The lever 82 is loosely mounted on the rocker shaft 91. Pivotally secured to the opposite end of the lever 82 is a pawl 92, which engages the teeth of gear 84 and prevents it from over-rotating beyond a predetermined position. The lever and pawl are controlled by both the cam surface on the disc 78 and by the rocker shaft 91; the pawl 92 is hooked at one end as indicated by 93.

The hook portion rests against the rocker shaft 91, which limits its movement in that direction. When the opposite end of the pawl engages the teeth of the gear 84, and when its movement is in a counter clockwise direction, it serves as a positive stop and prevents over-rotating. The pawl 92 is pivotally secured to the lever 82, and is constantly held in one direction by the tension of the spring 94, which is secured to pins mounted in the lever 82 and pawl 92 respectively. When the calculations are in subtraction and division, the gear 84 moves in a clockwise direction and the engaging tooth will force the pawl out of its path of rotation against the tension of the spring 94, and will drop into the space between the next teeth, thereby preventing it from over-rotating. When the reverse operation is taking place, the lever 82 and pawl 92 are controlled by the rocker shaft 91, lever 97, and cam 96, the latter being secured to the shaft 66. To bring this construction under control of the cam 96 when it rotates in a clockwise direction it wipes against the lever 97 which forces the finger 98 of the lever 97 against the arm 99, thereby rotating the rocker shaft 91 in a counter clockwise direction. This movement of rotation causes the pin 100 located on the rocker shaft 91 to engage the pin 101 and lift the lever 82 away from the cam surface formed on the disc 78. This operation causes the lever 82 to be held rigid for the purpose of allowing the pawl 92 which is held and operated

under the tension of the spring 94 to check in the reverse operation. The cam 96 holds the lever 92 in an upward position during one revolution until the lever 97 again enters the space cut out on the cam, and the lever 97 then drops back into the position shown in Figure 16.

In the addition of 5 and 5, which necessitates the use of the key 5 and the turning 10 of the operating crank twice, thereby revolving the dial one revolution and registering zero, and the next dial will register one thereby making a total reading of ten. This is accomplished by the mechanism 15 shown in Figures 8 and 15. Secured to the dial gear 85 is a pin 105, Figure 8. When the gear is rotated to either the last tooth, or to one-tenth of a revolution, the pin 105 engages the bevel end of arm 106, thereby 20 forcing it downwardly. When the dial gear travels in the reverse position the pin 105 engages the opposite side of the bevel; surface formed on the arm 106 also forcing it downwardly for the carrying-over operation. 25 The lever 106 is integral with the lever 107, the two levers being connected by the cross piece 108. The downward movement of the lever 106 is communicated to the lever 107 and causes it to be released 30 from the spring catch 109, at the same time, allowing the projection 110 formed on the lever 107 to drop into the path of the carrying-over mechanism 111. The catch 109 is secured to the stationary collar 113 by a 35 screw.

The carrying-over mechanism 111 is pivotally secured to the disc 78, as shown in Figures 7 and 7^A. The portion 115 of the carrying-over mechanism extends through 40 the disc and is pivoted through the lug 116, Figure 7^A, sufficient clearance being provided to allow the member to swing upwardly. Extending across to the next disc is an 45 arm 117, which is held from sidewise movement by the slot 118, Figure 7, but is free to move upwardly to the height of the slot as shown in Figure 7. The upper part of 50 the device is formed into two bevel cam surfaces 119 in the form of the letter A. Integral with this is the tooth portion 125, which 55 engages the gear 84 of the next set; that is, when the lever 107 drops down to the position shown in Figure 15, the bevel gear surface 119 wipes against it, and causes the 60 tooth portion 125 to move in the path of rotation to engage the tooth of the gear 84 of the next dial gear. Formed in the disc 78 is an offset projection 130, which in its 65 path of rotation comes into contact with the projection 110 formed on the lever 107.

By this construction the lever 107 is forced back into the spring catch 109, on the completion of the revolution of the disc 78 and the calculating operation is completed.

All operating parts work the same in both directions, with the exception of the over-rotation check and the carrying-over mechanism. The over-rotation check has been explained in detail. In the reverse 70 position a duplicate carrying-over mechanism 135 is employed. The construction and operation of the carrying-over mechanisms are identical, but it is set in position in the disc to allow the carrying-over operation to take place at the proper time. In the reverse operation, which is used in subtraction and division calculations, the carrying-over mechanism is located on five of 75 the discs. In order to prevent all five of 80 them operating together they are set in a spiral relation on the disc, and in relation to themselves, so that if one carrying-over mechanism operates at a certain time, the next one would be several degrees after the other, thereby preventing all of them operating together,

In operation, calculations are accomplished in addition, subtraction, multiplication and division. These calculations call 90 for distinct and complete operation of the mechanism. While other calculations and formulas can be worked out, the classification will explain the embodiment of my 95 invention.

The standard adding machine keyboard is used for setting up numbers to be added, subtracted and divided, and forms a part of the selecting mechanism. In proper relation to the keyboard is a suitable crank 23 100 for performing the operation of calculation. On the back of the machine is a carriage holding the dials, which shows the results and proofs of the operations as they are performed. The crank 23 can operate 105 clockwise and counter clockwise. In carrying out addition, the crank is turned in one direction, while in subtraction the crank is turned in the opposite direction. When the zero key is pressed downwardly, the crank 110 can be turned without effecting the selecting mechanism and dials. The carriage 13 showing the result, dials may be shifted to the right or the left with ease and accuracy to obtain the results in conjunction with the 115 selecting or operating mechanism. To obtain a result in addition or multiplication, any of the keys from 1 to 9 inclusive, in as many of the sets 17, 18, 19, 20, 21, 22, as desired, may be pressed downwardly and 120 held by the locks 53. The downward movement of the keys, excepting the zero key, would cause the sliding plate 40 to move to the right, thereby imparting a swinging movement to the bell crank lever 42. As the 125 bell crank lever 42 swings on its pivot it causes the selecting gear 56 to move axially within the range limited by the cage gear 80. The crank 23 is now turned one revolution, which causes the disc 78 to turn in the 130

direction of the arrow Figure 13. One of the gear bars from 1 to 9, will cause the gear 56 to turn according to the key that was previously set. This movement of operation of the gear 56 will impart a rotating movement to the cage gear 80, intermediate gear 84, and dial gear 85, thereby showing the result through the dial window 24. When the gear bar 9 engages or is in line with the gear 56, the over-rotating check lever 82 drops down to the lower cam surface, causing the pawl 92 to move out of the path of rotation of gear 84, thereby allowing the whole train of gears to rotate. After they have rotated to the position shown in Figure 14, the over-rotating check lever is raised to the upper cam surface, and the gears are again locked until the next operation. In subtraction and division 20 the crank 23 is turned in the opposite direction, one revolution, which causes the discs and selecting bars from 1 to 9 inclusive, to rotate in the opposite direction as well as all other rotating members, the results showing through the window 24 of carriage 13. During the reverse operation, the over-rotating check is again brought into action. When the shaft 16 rotates counter clockwise, or in the reverse movement, it carries with it the cam 96, which wipes against the lever 97, which swings causing the finger 98 to engage the arm 99 and imparts a rotating movement to the rocker shaft 91. As the lever 97 wipes over the outer surface of the cam 96 it holds the over-rotating check away from the cam surface formed on the disc 78 and the over-rotation checking function is transferred to pawl 92. As the gear 84 rotates in a clockwise direction, it will force the pawl downwardly at one end against the tension of spring 92, forcing it out of the path of rotation, when it will drop into the space between the next two teeth of the gears, thereby forming an effective check. Although the gear 84 is free to move clockwise against the tension of the spring, it would be impossible for it to move in the opposite direction, due to the hook portion 93, which strikes the rocker shaft and makes a positive lock.

In performing the carrying-over operation, the pin 105, located on tooth 9, wipes against the bevel surface of the yoke lever 106, causing the catch on the lever 107 to be released from the catch 109, permitting it to drop to the position shown in Figure 15. In the reverse movement the pin 105 engages the opposite side of the bevel surface formed on the arm 106 forcing it down in the same manner to complete the carrying-over operation. By this movement, the projection 110 is brought into the path of the bevel surface 119, causing it to pivot and swing outwardly into the path of the gear 56, thus imparting a rotating movement

thereto, and carrying the result up to the next dial. In the reverse movement, the operations are timed the same, except a duplicate lever 135 is employed for the carrying-over operation.

What I claim as new and desire to secure by Letters Patent of the United States is,—

1. In a calculating machine, a setting up mechanism including a slidable gear to be selectively set in any one of a plurality of positions, a cage gear with which the sliding gear cooperates in any position of the latter, a plurality of disks arranged beyond the sliding gear and adapted for manual operation, bars bridging the space between said disks and adapted to cooperate with the sliding gear, said bars being formed with operating projections of progressively less length in the circular plane of the disks, said projections directly engaging the respectively successive teeth of the slidable gear in accordance with the position of such gear. 70
2. In a calculating machine, a setting up mechanism, including a plurality of slidable gears adapted to be independently and selectively set at will, a cage gear with each of the slidable gears is adapted to cooperate, dial gears operated in the movement of the cage gears, a shaft arranged beyond the slidable gears, a plurality of disks on said shaft, and bars extending transverse the set of disks and engaging in the edges of each disk, said bars being formed between each pair of disks with tooth operating projections of progressively less length in the circular plane of the disks, the projections between any pair of disks controlling the operative movement of one of the slidable gears. 80
3. In a calculating machine, a setting up mechanism including a plurality of slidable gears, a cage gear for each slidable gear, a dial gear operated by each cage gear, a manually operable member for operating the slidable gears a number of teeth determined by their position, said member having a series of members of bar-like form common to all slidable gears but independently formed within the limits of movement of any one gear to operate such gear a number of teeth 105 determined by the position of the gear. 110
4. In a calculating machine, a setting up mechanism comprising a plurality of slidable gears, a cage gear for each slidable gear, means for operating the slidable gears a number of teeth in accordance with the positions of such gears, said means including a plurality of disks and bars connecting the disks, dial gears operated by the cage gears, and controlled by an overthrow check for 120 the dial gears operated directly by said disks. 125
5. In a calculating machine, a setting up mechanism comprising a plurality of slidable gears, a cage gear for each slidable 130

gear, dial gears operated in the movement of the slidable gears on their axes, and means for rotating the slidable gears, said means including a series of disks and bars connecting the disks and formed between each pair of disks to engage the slidable gears, the dial gear being acted upon by

overthrow checks, the edges of the disks being of cam formation to directly control the overthrow checks. 10

In testimony whereof I offer my signature this 19th day of November, 1919.

FRED W. BARKLEY.
